SIGNALING SYSTEM.

1,132,106.

Specification of Letters Patent. Patented Mar. 16, 1915.

Application filed October 24, 1910. Serial No. 588,693.

To all whom it may concern:

Be it known that we, HENRY B. MEAD and HERMAN F. GUENTZLER, citizens of the United States, residing at Cleveland, in the county of Cuyahoga and State of Ohio, have invented certain new and useful Improvements in Signaling Systems, of which the following is a specification.

This invention relates generally to signaling apparatus and particularly to devices of that type used for signaling from an office or similar place to different portions of a shop or plant to indicate the call for a foreman or other official no matter where he may be at the time.

Still more specifically the invention relates to a signaling system comprising a plurality of signals controlled and operated by a suitable selective device and commutator connected to the several alarms or signals and arranged in a manner such that the operator may select any call, and then set the apparatus in motion when the particular call selected will be sounded throughout the shop or plant until the operator shifts a controlling device when the device will cease to give the signal and the selective device will be released and free for manipulation in giving another signal, the selective device being locked during the operation of the signal. The arrangement of the mechanism is such that until the operator returns the controlling device the signal is repeated.

Further invention resides in certain details of construction hereinafter set forth in the following description, drawings and claims.

Referring to the drawings, Figure 1 is a front elevation of the cabinet together with a diagrammatic showing of the alarm system; Fig. 2 is a rear elevation of the cabinet with the back open to show the interior mechanism; Fig. 3 is a sectional view upon the line 3—3 of Fig. 2; Fig. 4 is a top plan view of the controlling lever; Fig. 5 is a detail view of the switch; and Fig. 6 is a detail view of the gearing.

In carrying out the invention any preferred form and construction of parts may be employed so long as they possess the necessary characteristics, but we have shown one form in the drawings which is highly effective in operation, and in such embodiment, 1 and 2 represent signals in the form of bells in a circuit composed of wires 3 and

4 which lead to a battery 5 on the one hand and to a cabinet 6 on the other. The arrangement of this mechanism is as follows:—There are alarm signals or bells placed at suitable distances apart in the shop or plant and they are all wired to a battery and to the cabinet so that upon a completion of the circuit in the line all the bells or alarms are sounded, the bells preferably being single-strike bells.

The cabinet 6 contains the operating and controlling mechanism, or the mechanism for giving or sounding the signals and comprising a suitable frame or plate 7 secured against the front wall of the cabinet and having mounted thereon a suitable motor 9 provided with a shaft 10 and a worm 11 mounted upon an insulating sleeve 12 secured to the shaft. This worm 11 meshes with a worm wheel 13 mounted upon a shaft 14 supported by a bracket 15 on the frame 7. This shaft 14 is also provided with a driving pinion 16 meshing with a relatively large gear wheel 17 mounted upon a pin 18 secured in the frame or plate 7. This gear wheel has secured to one side face thereof a suitable camming disk 19 having a continuous unbroken periphery, except for one-fourth of the entire circumference, there being at this point an abrupt recess 20 for a purpose to be described. The gear wheel 17 also constitutes an auxiliary commutator and is provided upon one of its faces, and for substantially a half of its circumference, with an insulating strip 21 secured to the side face of the wheel in any preferred manner. The gear wheel is still further provided with a crank pin 22 engaging in a slot 23 of a brush lever 24. This brush lever is pivoted upon a pin 25 secured in the frame and has one of its arms extending out beyond the pivot and there provided with a brush 26 insulated therefrom by a block of insulation 24' and secured thereto by a bolt 26'. This brush is adapted for engagement with the side face of a main commutator wheel 27 which is mounted upon a shaft 28 supported in the frame 7 and extending out through the front of the cabinet. This commutator wheel 27 is provided upon the face adjacent to the brush lever with projections 29 forming contact segments and arranged at predetermined points along spoke-like portions of the commutator wheel. These projections or segments are flush with

the surface of insulator strips 30 mounted over the side face of the entire wheel and forming a flat continuous surface and accommodating the travel of the brush 26. The spoke-like portions of the wheel extend from the center to the periphery thereof in a manner such that they coincide with the arc described by the brush mounted upon the brush lever 24, as it moves upon its pin 25 so that whenever one of the spoke-like portions of the commutator wheel is under the brush and the latter is moved through its path of movement, the brush will follow along the same and make contact with the several projections or segments thereon.

The signaling circuit is connected by a wire 32 forming a continuation of one of the wires 3 and 4 with the brush 26 and by a wire 31 forming a continuation of the other one of such wires, with a brush 33 secured to but insulated from the frame in any suitable manner. This brush 33 engages the auxiliary commutator or the side face of the gear wheel 17. The arrangement of these parts is such that as the lever 24 is being rocked in a counter clockwise direction and its brush is traveling upward over the commutator wheel, the brush 33 is also engaging the exposed side face of the wheel so that the signal circuit is closed throughout the device, when the brush 26 engages the several projections or segments of the commutator portion with which it is in engagement at that time. In this way the proper signal is given. In every instance where a device of this character is used, there are a number of signals to be given and these signals are made up upon the spoke commutator portions of the commutator wheel, that is, for example, there is a circular segment near the center and this will naturally give one ring so that one of the spoke members of the commutator wheel is blank, except for this ring. The next "member" has a commutator segment at a distance beyond the ring 30' so that there will be two operations of the alarm, and this feature is continued around the several spoke portions of the wheel for the different signals to be given. Upon the return movement of the brush 26 or when the lever is rocked in a clockwise direction, the brush 33 is engaging the insulated portion of the wheel 17 and the signal circuit is broken.

In order to select the proper signal or the proper commutator portion, the cabinet is provided upon its front with a plate 36 in the form of a dial and it contains the several indications or several signals which are to be given. At each one of these signals there is a notch 37 which receives a projection 38 carried by an operating lever 39 mounted upon the shaft 28. By means of this lever, 65 the commutator wheel is shifted from one

notch to the other and when it is in a notch the corresponding commutator spoke portion is in the proper position under the brush 26.

The operation of the motor is under the 70 control of a lever which is manually thrown into operation to start the device but may be automatically thrown out of operative position by the device itself, provided the operator has set it to perform this function. 75 This mechanism comprises a switch lever 40 mounted upon a pin 41 and provided with a lug 42 at one end for engagement with the periphery of the cam disk 19 and normally held in engagement with the periphery of said disk by a spring 43 secured to the frame. The opposite end of this lever, as shown in Fig. 5, has secured to it a knife switch member 44 mounted between insulating strips 45 and 46. All of these parts are secured to the lever 40 by means of screws 47. This knife switch member engages leaf switch members 48 and 49, the former being connected by a wire 50 with suitable resistance coils 51 and the latter 90 being connected by a wire 52 with the motor. Suitable electric connections from any source of supply lead to the resistance coil on the one hand and to the motor on the other, so that the circuit to the motor is 95 closed, except when the switch 44 is out of engagement with the leaf switch members 48.

In order to lock the commutator wheel after it has been set and before any signal 100 has been given, we provide suitable notches 53 upon the periphery of this wheel, and these notches are engaged by a lug 54 projecting from the lever 40 so that when the lower end of the lever 40 is thrown to the 105 right and the knife switch member 44 is in engagement with the switch members 48 and 49 and the circuit is completed through the device to the motor, the lug 54 is in engagement with one of the notches 53 and 110 the commutator wheel is locked against rotation until the lever 40 is out of such position. Normally the switch lever 40 has a tendency to shift in a clockwise direction so that the knife switch member 44 is out 115 of engagement with the switch members 48 and 49, but such position is only possible when the lug 42 is in the recess 20 of the cam disk 19, but when it is in this position the entire device is at rest and no current 120 is being supplied to the motor.

Suitable mechanism is provided for manipulating and shifting this lever in a counter clockwise direction to bring the knife switch member 44 into engagement with the other switch members, and it comprises an operating lever 55 pivoted upon a pin 56 mounted upon a bracket 57 secured to the framework and projecting out through the front of the cabinet where it is provided 130

with a finger piece 58 by means of which it may be shifted back and forth in a slot 59 in the cabinet. This operating lever is provided with a screw 61 upon its upper face and passing through a slot 62 in a link 63 which is pivotally secured by means of a screw 64 to the lever 40, the arrangement being such that when the finger piece 58, as shown in Fig. 1 in the front of the cabinet, 5 is shifted to the left, the link 63 shifts the lower end of the lever 40 to the left causing the knife switch member 44 to engage between the switch members 48 and 49 when current will be supplied to the motor and 10 the lug 42 will be raised out of the recess 20 of the disk 19, the motor being then free to drive the wheel 17 and operate the brush lever in a manner already described, but after the motor has once started or has run 15 sufficiently so that the lug 42 is raised above the periphery of the disk 19, then the operating lever may be shifted back into initial position and the device will continue to give the signal and will automatically shut off 20 when the lug 42 reaches the recess 20 when it will drop into the same and the lever 40 will be shifted in a clockwise direction, causing the knife switch member to be thrown out of engagement with the other 25 switch members, thus breaking the circuit of the motor and stopping the operation of the device. The return of the operating lever is permitted as above outlined by reason of the slot and pin connection between 30 it and the switch lever 40.

It is desirable to have the operating lever 35 assume either the extreme right or left position positively and this is brought about by means of a wire spring 65 secured to the bracket 57 and to the lever, the former being provided with a shoulder 66 forming camming portions on each side thereof for coöperating with a screw 67 secured to the operating lever 55 and serving to hold it in 40 one position or the other. It is quite obvious that when the lever 55 is held in the on position, the lever 40 will be held in operative position with the knife switch in engagement, causing the motor to continue to drive 45 the mechanism.

Having described our invention, we claim:—

1. Calling apparatus for shops and the like, a contact member having a plurality of 50 contact portions, one for each call, brush mechanism for engaging said contact device, means for producing a relative movement between the contact member and the brush mechanism, and controlling means for permitting said apparatus to operate and produce a single operation of any call and to further cause the operating mechanism to automatically repeat the call.

2. Commutator mechanism for electrical 55 signals comprising a commutator member

having a plurality of commutator portions each corresponding to a call or signal, a brush member provided with a brush adapted to engage any one of said commutator portions when the latter is in the proper 70 position, means for shifting said brush back and forth across the commutator portion, and mechanism for controlling the operation of said brush member including a device which when in one position causes the 75 signal to be given once only, and when in another position holds the mechanism in position to repeat the signal until released.

3. Commutator mechanism for electrical 80 signals comprising a commutator member having commutator portions, a brush member coöperating with said portions and supported to engage any one of said portions when the latter is in the proper position, a motor for producing a relative movement of 85 the commutator and the brush member, a circuit controller for said motor, means for breaking the circuit after a single operation of the device in the production of a call, and manually operated means for starting the 90 motor and including instrumentalities for permitting the automatic stopping of the motor after a single operation and for holding the controlling mechanism in operative 95 position to cause the device to repeat its operation in repeating a signal.

4. Commutator mechanism for electrical 100 signals comprising a commutator member having commutator portions, a brush member supported to engage any one of said 105 commutator portions when the latter is in the proper position, a motor for shifting said brush member, a switch for controlling said motor, means normally tending to shift said switch into the off position, means operated by the motor for holding said switch in closed position during a predetermined 110 movement of the brush member, and means for initially operating said switch.

5. Commutator mechanism for electrical 115 signals comprising a commutator member having commutator portions, a brush member mounted to engage any one of said 120 portions when the latter is in the proper position, a motor for shifting said brush member, a switch for controlling said motor, means normally tending to shift said switch into the off position, means operated by the motor for holding said switch in a closed position during a predetermined movement 125 of the brush member and then releasing the switch to its normal tendency, and an operating device for shifting said switch to bring about the initial starting of the device.

6. Commutator mechanism for electrical 130 signals comprising a commutator member having commutator portions, a brush member supported to engage any one of said portions when the latter is in proper position, a motor for shifting said brush mem-

ber, a switch for controlling said motor, means normally tending to shift said switch into the off position, means operated by the motor for holding said switch in a closed position during a predetermined movement of the brush member and then releasing the switch during its normal tendency, and an operating lever adapted when in one position to start the device and hold the switch closed, and when in another position to permit the switch member to return to its normal position at the end of the movement of the brush member.

7. Commutator mechanism for electrical signals comprising a commutator member having commutator portions, a brush member supported to engage any one of said portions when the latter is in proper position, a motor for shifting said brush member, a switch for controlling said motor, means normally tending to shift said switch into the off position, means operated by the motor for holding said switch in a closed position during a predetermined movement of the brush member and then releasing the switch to its normal tendency, an operating lever adapted when in one position to start the device and hold the switch closed, and when in another position to permit the switch member to return to its normal position at the end of the movement of the brush member, and a spring for holding said operating lever in either of its two positions.

8. Commutator mechanism for electrical signals comprising a commutator member having commutator portions one for each call, a brush member mounted to engage any one of said commutator portions when the latter is in the proper position, means for operating said brush member, a selective device for selecting the proper commutator portion, means for holding the commutator member in the selected position, and means under the control of the brush operating mechanism for positively locking the commutator member during the movement of the brush member.

9. Commutator mechanism for electrical signals comprising a commutator wheel having substantially radially disposed commutator portions one for each call, a brush member mounted to travel over any one of said commutator portions when the latter

is in proper position, a motor for shifting said brush member, a switch for controlling said motor, means for holding said switch in a closed position during the operation of the device, and means carried by the switch member for locking the commutator wheel against rotation during the operation of the device.

10. Commutator mechanism for electrical signals comprising a commutator wheel having a plurality of commutator portions and a shoulder on the periphery corresponding to each commutator portion, a brush member mounted to engage any one of said commutator portions when the latter is in proper position, a motor for shifting said brush member, a switch member carrying a switch for controlling said motor, means for holding said switch member with the switch in a closed position, a projection carried by said switch member for engagement with one of the shoulders on the periphery of the commutator wheel to hold the same locked during the operation of the device, and means for selecting the proper commutator portion.

11. In a signaling system, a signal circuit, and commutator mechanism for closing said circuit and consisting of a frame, a commutator wheel rotatably mounted upon said frame, commutator portions carried by said wheel, a brush lever pivotally mounted upon the frame, a brush carried by said member and insulated therefrom and connected to one side of the signal circuit, a suitable motor for shifting said lever to cause its brush to move back and forth along one of the commutator portions when in proper position, an auxiliary commutator wheel operated by the motor, and a brush co-operating therewith, said auxiliary commutator and brush being adapted to break the signal circuit during one cycle of movement of the main commutator brush.

In testimony whereof we affix our signatures in presence of two witnesses as follows.
